UNITED STATES PATENT OFFICE.

RUDOLF LANGHANS, OF BERLIN, GERMANY.

INCANDESCENT GAS-LIGHTING.

1,083,936.

Specification of Letters Patent.

Patented Jan. 13, 1914.

Application filed May 14, 1912. Serial No. 697,184.

To all whom it may concern:

Be it known that I, RUDOLF LANGHANS, a subject of the Emperor of Austria-Hungary, and whose residence is No. 9 Schönhauser 5 Allee, Berlin, Kingdom of Prussia, German Empire, have invented a new and useful Improvement in Incandescent Gas-Lighting, of which the following is a specification.

10 My invention relates to upright incandescent gas burners with suspended mantle.

Heretofore in burners of that class the mantle is generally suspended from a holder or support mounted on a prolonged 15 part of the upright gas-mixing-tube which passes through the mantle. This system has many disadvantages. In passing the mantle over the gas-mixing-tube, the edges of the lower opening in the mantle are very 20 easily injured and this leads to a disproportionate consumption of the fragile mantles. The prolonged part of the tube passing through the mantle diminishes considerably the lighting effect by conducting 25 off heat and by absorbing a considerable amount of light reflected by the inner wall of the mantle. Furthermore the fitting and exact adjustment of the mantle on the burner require a wearisome and minute manipulation. In order to avoid these disadvantages the mantle is in accordance with 30 the present invention suspended from and centered by the transparent chimney of glass, quartz-glass or a similar transparent 35 material or by the holder of the chimney which is in turn mounted adjustably in longitudinal direction relatively to the gas mixing tube.

In the accompanying drawings Figure 1 40 is a longitudinal section of a burner constructed in accordance to the invention. Fig. 2 is a view of a modified form of the mantle adapted to be used in the burner of Fig. 1. Figs. 3 and 4 are sections similar to 45 that of Fig. 1 of two further modifications of the burner. Fig. 4^a is a fragmentary section of another modification. Fig. 4^b shows another modification in fragmentary section and fragmentary elevation. Figs. 5 50 and 6 are segregated details showing modifications of my invention, said figures being combined side elevations and sections.

In Fig. 1 *a* is the nozzle, *b* the gas mixing tube screwed on the nozzle *a* and *c* the upper detachable slotted head thereof. Adjustably mounted relatively to the mixing

tube preferably by screwing on the nozzle *a* is a sleeve *d*. *f* is the chimney of glass, quartz-glass, or other transparent material. The chimney is provided with openings *o* 60 for the admission of air and has on its lower part a narrow mouth or cylindrical socket *e* preferably but not necessarily provided with a metal sleeve *e*¹ which may be fastened to the glass socket *e* by a suitable 65 cement. The socket *e* with or without the sleeve *e*¹ fits into the cup shaped sleeve *d* so that the chimney *f* is held centrally and is prevented from tilting by the sleeve *d* and that it may also be readily and exactly 70 adjusted in a longitudinal direction relatively to the mixing tube *b* and its slotted head *c* by turning the screw threaded sleeve *d*. The top of the chimney *f* is provided with a cylindrical socket *g* for suspending 75 and centering the mantle *m*. The mantle *m* is fastened in a usual manner on the mantle-supporting ring *h* preferably of ceramic material and provided in a known manner with three or more upright arms *h*¹ 80 having lugs *i*. The arms *h*¹ are provided with ribs *k* as means for guiding and centering the ring *h* and the mantle *m* on the chimney *f* and consequently also relatively to the mixing tube *b* and its slotted head *c*. 85 The ring *h* resting with the lugs *i* on the socket *g*, the mantle *m* can be easily and exactly adjusted in height relatively to the slots of the head *c* by turning the sleeve *d*. Suspended from the ring *h* is an annular 90 cup *l* as means for guiding the flame in the upper part of the mantle *m* along the inner wall of the same. In the modification shown in Fig. 2 the separate guiding member is omitted. Means for guiding the 95 flame in the upper part of the mantle and along the inner wall of the same, are provided by having the inner diameter of the mantle-ring *h* reduced in size to correspond to the outer diameter of the slotted head, 100 the mantle *m* being constructed with a pear-like frame. Furthermore the ribs *k* of Fig. 1 are substituted by the downwardly directed hooks *h*¹ of the lugs *i*, so that in this case the ring *h* is guided and centered 105 on the outer circumference of the socket *g* of the chimney *f*.

In Fig. 3 the mouth or socket *e* of the chimney *f* is omitted and the sleeve *d* is provided with uprights *p*, preferably three, of 110 wire connected with a ring *q* for supporting a downward bent flange *r* of the chimney

socket *g*. The prolonged ends of the wire-uprights *p* guide and center the chimney *f* and the latter in turn guides and centers the mantle ring *h* by the ribs *k* in the same manner as in Fig. 1.

In Fig. 4 the chimney *f* is fitted in the sleeve *d* but the mantle-ring *h* is suspended, guided and centered by means of a ring *s* detachably mounted on a connecting ring *q*¹ of wire uprights *p* provided in the same way as in Fig. 3 on the sleeve *d*.

It is obvious that in all the modifications shown the interior of the incandescent mantle is absolutely free from any heat or light absorbing body, that the mantle can be easily and exactly adjusted in relation to the slots of the slotted head of the mixing tube and that any exchange of the mantle by the consumers can be effected very readily and without danger of injuring the edges of the mantle openings.

Various constructional modifications may be made within the scope of the invention. Thus, for the thread connection of the sleeve *d* with the nozzle *a* may be substituted a thread connection of the sleeve with the mixing tube (see Fig. 4^a), or a pin *b'* and inclined slot *d'* as shown in Fig. 4^b.

The chimney *f* shown in the drawings (Figs. 1-3) as consisting of one piece may consist of two or more pieces of a cup shaped bottom part and a cylindrical upper part fitting on into the other preferably with ground in edges (Fig. 5), or of a cup shaped bottom part, a cylindrical middle part and a shoulder-shaped annular upper part also fitting together (Fig. 6). The holes or openings for admission of the air may be provided in such cases either in the cup-shaped bottom part (Fig. 5) or near the lower edge of the cylindrical middle or upper part (Fig. 6) respectively.

What I do claim as my invention, and desire to secure by Letters Patent of the United States, is:—

1. In an upright incandescent gas burner with suspended mantle the combination of a gas mixing tube having a nozzle and a slotted head with its upper end disposed adjacent to the bottom of said mantle, a sleeve mounted adjustably in longitudinal direction relatively to the said mixing tube, a chimney of transparent material, a mantle ring suitably mounted to partake of the adjustable movements of said sleeve and carrying an incandescent mantle with an opening at the bottom for passing the slotted head of the mixing tube, and means for guiding the mantle into a central position relatively to the said slotted head, substantially as set forth.

2. In an upright incandescent gas burner with suspended mantle the combination of a

gas mixing tube having a nozzle and a slotted head with a sleeve mounted adjustably in longitudinal direction relatively to the said mixing tube, a chimney of transparent material, fitting with a narrow mouth into the said sleeve and supporting a mantle ring carrying an incandescent mantle with a bottom opening for passing the slotted head of the mixing tube and means for centering the said mantle relatively to the said slotted head, substantially as set forth.

3. In an upright incandescent gas burner with suspended mantle the combination of a gas mixing tube having a nozzle and a slotted head with a sleeve mounted adjustably in longitudinal direction relatively to the said mixing tube, a chimney of transparent material, fitting with a narrow mouth into the said sleeve and supporting a mantle ring carrying an incandescent mantle with a bottom opening for passing the slotted head of the mixing tube, guiding members formed on the mantle-ring for centering the said mantle in relation to the said slotted head, substantially as set forth.

4. In an upright incandescent gas burner with suspended mantle the combination of a gas mixing tube having a nozzle and a slotted head with its upper end disposed adjacent to the bottom of said mantle, a sleeve mounted adjustably in longitudinal direction relatively to the said mixing tube, a chimney of transparent material carried by said sleeve, a mantle ring carrying the incandescent mantle which has an opening at the bottom for passing the slotted head of the mixing tube, means for centering the mantle relatively to the said slotted head and means for guiding the flame within the upper part of the mantle along the inner wall of the mantle, substantially as set forth.

5. In an upright incandescent gas burner with suspended mantle the combination of a gas mixing tube having a nozzle and a slotted head with a sleeve mounted adjustably in longitudinal direction relatively to the said mixing tube, a chimney of transparent material carried by said sleeve, a mantle ring the inner diameter of which corresponds with the outer diameter of the said slotted head carrying an incandescent mantle of pear like form having a bottom opening for passing the slotted head of the mixing tube, substantially as set forth.

In testimony whereof I have hereunto set my hand in presence of two subscribing witnesses.

RUDOLF LANGHANS.
